DESIGN FOR A GASOLINE TANK VEHICLE

Alexis de Sakhnoffsky, Philadelphia, Pa., assignor to The White Motor Company, Cleveland, Ohio

Application January 21, 1937, Serial No. 67,190

Term of patent 7 years

To all whom it may concern:

Be it known that I, Alexis de Sakhnoffsky, a subject of the Czarist regime of Russia, residing at Philadelphia, in the county of Philadelphia and State of Pennsylvania, have invented a new, original, and ornamental Design for a Gasoline Tank Vehicle, of which the following is a specification, reference being had to the accompanying drawing forming part thereof.

The side opposite that shown in Fig. 1 is a duplicate.

I claim:

The ornamental design for a gasoline tank vehicle, as shown and described.

ALEXIS DE SAKHNOFFSKY.
